UNITED STATES PATENT OFFICE.

VICTOR R. DESPARD, OF VALPARAISO, INDIANA, ASSIGNOR TO MCGILL MANUFACTURING COMPANY, A CORPORATION OF INDIANA.

BRACKET SOCKET.

Application filed October 30, 1925. Serial No. 65,778.

My invention relates to electrical sockets and more particularly to a bracket socket.

It is a purpose of my invention to provide a new and improved combined switch mechanism and socket member and to provide new and improved means for mounting the lamp socket terminals and the switch mechanism thereon.

It is one of the purposes of my invention 10 to provide new and improved means for mounting a lamp terminal upon an insulating support whereby a single securing member holds the lamp terminals in position on the insulating support. In the preferred 15 form, said means comprises an arcuate member engaging with suitable means such as an inwardly directed flange, on the screw shell terminal of a lamp socket which is provided with an ear extending adjacent the insulating means, said screw shell being also provided with an ear extending adjacent said insulating means on the opposite side thereof and a single fastening member passing through said ears and said insulating 25 means for securing the screw shell in position thereon.

It is another purpose of the invention to provide new and improved means for insulatingly mounting lamp terminals in cooperation 30 relation with a switch mechanism comprising a pair of insulating members which are carried by a suitable support or switch frame for the movable element of the switching mechanism at one end thereof, 35 said lamp terminals being mounted at the other end thereof so as to be insulated from the support and from the movable switch member when in open circuit position.

It is another purpose of the invention to 40 provide new and improved means for mounting a switch mechanism and lamp terminals comprising a pair of insulating members which are preferably made of sheet insulating material which are carried by a 45 switch frame at one end thereof whereby the same are held in properly spaced and relatively fixed relationship at said end and which are connected and held in properly spaced and relatively fixed position at the 50 other end thereof by a pair of members of conducting material so that a rigid rectangular framework is formed of said insulating members, conducting members and switch framework. The conducting mem-

bers preferably have a contact mounted on 55 each thereof, which contacts are bridged by the moveable switch element of the switching mechanism, said contacts being mounted between the insulating members and one of the conducting members having one of the 60 lamp terminals, preferably the center contact, provided thereon and the other conducting member having a wiring terminal provided thereon.

It is another purpose of the invention to 65 provide a device of the above mentioned character with suitable pull operated actuating mechanism comprising a longitudinally movable actuating member connected with the switch mechanism and normally retracted by a resilient member and means for moving said actuating member against the tension of said spring comprising a lever engaging said actuating member and fulcrumed on a bracket depending from the 70 supporting means for the switch element and furthermore, providing said lever with stop means thereon engaging a portion of said bracket to limit the retractile movements of the lever and actuating member. 75

Other objects and advantages of the invention will appear as the description of the drawings proceeds. However, I desire to have it distinctly understood that I do not intend to limit myself to the exact details 80 shown or described but that I intend to include as part of my invention all such obvious changes and modifications of parts as would occur to a person skilled in this art and as would fall within the scope of the 85 claims.

In the drawings:

Fig. 1 is a side elevation of my improved switch mechanism and lamp socket member with the outer insulating tubular member in 90 section;

Fig. 2 is a similar view taken at right angles to Fig. 1;

Fig. 3 is a section taken on the line 3—3 of Fig. 1;

Fig. 4 is a section taken on the line 4—4 of Fig. 1;

Fig. 5 is a fragmentary section taken on the line 5—5 of Fig. 1; and

Fig. 6 is a section taken on the line 6—6 of Fig. 2.

Referring in detail to the drawings, my improved switch mechanism comprises a

switch frame 10 upon which is mounted a movable contact arm 11, said arm being pivoted on the insulating pivot members 12 and being operated by suitable actuating mechanism, such as that shown in the patent to Gordon, No. 1,473,224, patented November 6, 1923, the details of this mechanism not being a part of this invention. For the purposes of this invention, it suffices to say that the actuating mechanism comprises a spring 13 which produces a snap action of the movements of the movable switch arm 11 and also serves to retract or move inwardly the projecting actuating member 14.

15 A pair of flat sheet insulating members 15 are carried by the switch frame 10, said switch frame having paired lugs 16 extending through paired openings 17 in the members 15 to properly position the members 15 relative to the frame 10, said members being furthermore secured together at the lower ends thereof by means of at least one transversely extending securing and spacing member 18 which is provided with paired projections 19 extending through suitable openings in the members 15 and clinched over so as to secure said members firmly together at their lower ends. A finger 20 and a pair of fingers 21 are provided on the member 18 projecting outwardly therefrom, the member 20 projecting into a suitable opening 22 in the tubular insulating covering 23 and the members 21 serving as stop flanges for limiting the downward movement of the member 23 on the combined switch and lamp socket device.

25 At their upper ends, the members 15 are secured together and held in properly spaced relationship by means of the conducting cross members 24 and 25 which are provided with the paired projections 26 that are upset so as to secure the members 15 together and properly space the same and also prevent twisting of the members 15. Due to the provision of the paired projections 16, the member 18 and the members 24 and 25 connecting the members 15 together, a very substantial and rigid box-like frame-work made up of said members is provided.

30 The members 24 and 25 have the contact members 27 and 28 provided thereon which are adapted to be bridged by the contact 11 as shown in Fig. 6. The contacts 27 and 28 may be of any desired form, but are shown as converging from the members 24 and 25 toward the free ends thereof and terminating in convex contact making portions 29. The ends thereof that are secured to the members 24 and 25 are turned substantially 35 at right angles to the converging portions thereof and are made somewhat wider as indicated at 30 so as to provide for sufficient material for the rivets 31 by means of which the same are secured to the members 24 and 25. The member 24 is also provided with a

binding screw 32 which serves as one of the wiring terminals of the device and the member 25 is provided with an upwardly extending ear 33 upon which is mounted the center contact 34 of the lamp socket.

70 The lamp socket is provided with a screw shell 35 as is customary and said screw shell is provided with an inturned lip or flange 36 that is arcuate in shape and is provided with a break therein at 45. Engaging said flange 36 is a holding member having an arcuate body portion 37 overlying the flange 36 and provided with depending apertured ears 38 and 39 which have screw-threaded openings for receiving the screw-threaded securing member or bolt 40. A depending apertured ear 41 is also provided on the screw shell 35 which lies between the head 42 of the screw or bolt 40 and the ear 39. The screw or bolt 40 also passes through suitable openings in the members 15 and it will be seen that when the member 40 has passed through the various openings, the same will hold the screw shell firmly in position on the insulating members 15. In 90 order to positively hold the screw shell from rotation relative to the insulating members 15, the flange 36 is widened at a plurality of points indicated by the numeral 43 and cut away between said thickened portions so as to provide pairs of shoulders 44 between which the down-turned ears 38 and 39 lie, the holding member 37 and the screw shell 35 thus being interlocked so that the screw shell will not rotate relative to the 100 holding member.

95 An insulating gasket or washer 46 is mounted between the end of the shell 35 and the ends of the members 15 and is provided with an opening 47 in the form of a slot 105 through which the ear 38 projects and with a notch 48 through which the ears 39 and 41 project. The washer 46 is further provided with an opening 49 for the extension 33 of the member 28 so that the same may be passed therethrough and the center contact 34 placed in the proper position in the socket. It will be seen that the washer or gasket 46 is held firmly in position between the screw shell 35 and the members 15 when 115 the fastening member 40 is put in place. Upwardly extending ears or tongues 50 are provided on the members 15 seating in the notch 48 and the slot 47 to furthermore hold the parts in proper relationship to each 120 other.

125 The screw 40 acts as a wiring terminal screw, the end of a conductor being insertable below the head 42 of the screw and between the same and the ear 41, the same being clamped in position by means of the screw. In order to insulate any strands of the conductor that might accidentally come in engagement with the projections 26, a 130 layer of insulating material 51 is inserted 135

between the ear 39 and the member 15, having an opening 52 therein through which the screw 40 passes.

Secured to the switch frame 10 is a bracket 53, the upper transversely extending portion 54 of said bracket being secured to the member 10 in any desired manner and having an opening 55 therein through which the actuating member 14 extends. The bracket 10 is provided with an offset at 75 and with a lower end portion 56 extending transversely to the main body portion of the bracket. An internally threaded sleeve 57 is secured thereto in any desired manner.

15. The vertically extending portion of the bracket 53 is provided with a pair of closely spaced openings 58 which are separated by means of the web 59. An oblong opening 60 is provided in the member 14 and the lever 61 extends through said opening 60 having a notch 62 therein for positioning the member 14 relative thereto. One end of the lever 61 is provided with a pair of hook-like fingers or bifurcations 63 which are 25 bent around the web 59 extending through the openings 58, thus pivoting the lever 61 on the web 59, the web 59 acting as a fulcrum for the lever. As will be clear from Fig. 2, the lever is made of two pieces of 30 sheet metal which lie face to face and are secured together by means of the rivet 64. The end of the lever 61 opposite the bifurcated end thereof, is flanged outwardly from the center thereof as indicated at 65 and has a pair of parallel flanges 66 thereon forming a channeled guide for the pull chain 67, said pull chain being mounted in the end flange 68 provided in said channeled portion of the lever. The upper edge of 40 the lever is provided with an outward projection 69 which is adapted to engage against the transversely extending upper end 54 of the bracket 53 to limit the upward movement of the lever 61 due to the retractile effort of the spring 13. A notch 70 is provided in the member 23 to provide clearance for the lever 61 so that the same will not strike against the tube 23, but against the metallic member 54.

50. Obviously, the screw-threaded sleeve 57 is threaded onto a screw-threaded nipple or other means for mounting the socket and switch mechanism in position. The bracket 53 mounted thereon in turn supports the supporting member or switch frame 10 which carries the insulators 15, which insulators in turn carry the lamp socket and wiring terminals.

Having thus described my invention, 60 what I desire to claim and secure by U. S. Letters Patent is:

1. In a device of the character described, a screw shell having an inturned flange and an apertured ear extending from said flange, insulating supporting means for said screw

shell, a holding member engaging said flange within said screw shell and provided with an apertured ear projecting therefrom to the exterior of said shell and securing means passing through said apertures and said insulating supporting means.

2. In a device of the character described, a screw shell having an inturned flange and an apertured ear thereon, insulating supporting means for said screw shell, an arcuate holding member engaging said flange within said shell and provided with an apertured ear projecting outside said shell and a single securing means passing through both of said apertures and said insulating supporting means.

3. In a device of the character described, a screw shell having an inturned flange and an apertured ear thereon, insulating supporting means for said screw shell, a holding member engaging said flange provided with apertured ears at opposite ends thereof and a single securing means passing through both of said apertures and said insulating supporting means.

4. In a device of the character described, a pair of insulating members, means for maintaining said insulating members in predetermined spaced relation, a screw shell having an inwardly directed flange and an ear extending from said flange, a member engaging said flange provided with an ear projecting therefrom and means extending through said insulating members and said ears to secure said screw shell on said insulating members.

5. In a device of the character described, a pair of insulating members, means for maintaining said insulating members in predetermined spaced relation, a screw shell having an inwardly directed flange and an ear extending from said flange, a member engaging said flange provided with an ear projecting therefrom, an insulating gasket mounted between said shell and said pair of insulating members and means extending through said insulating members and said ears to secure said screw shell on said insulating members.

6. In a device of the character described, a pair of insulating members, means for maintaining said insulating members in predetermined spaced relation, a screw shell having an inwardly directed flange and an ear extending from said flange, a member engaging said flange provided with an ear projecting therefrom, an insulating gasket mounted between said shell and said pair of insulating members and having openings for receiving said ears and means extending through said insulating members and said ears to secure said screw shell on said insulating members and said gasket therebetween.

7. In a device of the character described, a pair of insulating members, means for maintaining said insulating members in predetermined spaced relation, a screw shell having an inwardly directed flange and an ear extending from said flange, a member engaging said flange provided with a pair of ears projecting therefrom, one of said ears lying adjacent the ear on said screw shell and a single member extending through said insulating members and said ears to secure said screw shell on said insulating members.

8. In a device of the character described, a pair of insulating members, means for securing said insulating members in spaced relation to each other, a screw shell, an insulating member mounted between said screw shell and said paired insulating members, a pair of members extending endwise from said shell through openings in said insulating member, and a single fastening means securing said endwise extending members to said paired insulating members.

9. In a device of the character described, a pair of insulating members, means for securing said insulating members in spaced relation to each other, a screw shell, an insulating member mounted between said screw shell and said paired insulating members, a plurality of spaced ears extending from said shell through openings in said insulating member into adjacency to said paired insulating members and fastening means passing through said ears and both of said paired insulating members.

10. In a device of the character described, a pair of insulating members, means for securing said insulating members in spaced relation to each other, a screw shell, an insulating gasket mounted between said screw shell and said paired insulating members, a plurality of spaced ears extending from said shell through openings in said insulating gasket into engagement with the outer faces of said paired insulating members and fastening means securing said ears to said paired insulating members.

11. In a device of the character described, a movable switch element, a supporting frame therefor, said element being insulated from said frame, a pair of insulator members secured to said frame in spaced relation to each other adjacent one end thereof, lamp socket terminals carried by said insulating members adjacent the other end thereof, and a pair of spaced conducting members spacing said insulating members from each other, one of said spaced conducting members having one of said terminals mounted thereon and the other spaced conducting member having a wiring terminal.

12. In a device of the character described, a movable switch element, a supporting frame therefor, said element being insulated from said frame, a pair of insulating mem-

bers secured to said frame in spaced relation to each other adjacent one end thereof, lamp socket terminals carried by said insulating members adjacent the other end thereof, and a pair of spaced conducting members spacing said insulating members from each other, each of said spaced conducting members having a contact thereon, said contacts being bridged by said movable switch element in one position thereof, one of said spaced conducting members having one of said terminals mounted thereon and the other spaced conducting member having a wiring terminal.

13. In a device of the character described, a pair of elongated insulating members, a switch frame mounted between and spacing said insulating members at one end thereof, and a wiring terminal support and a lamp socket terminal support securing said insulating members together in spaced relation at the other end thereof.

14. In a device of the character described, a pair of elongated insulating members, a switch frame mounted between and spacing said insulating members at one end thereof, a movable contact mounted thereon, a wiring terminal support extending between said insulating members and a lamp socket terminal support securing said insulating members together in spaced relation at the other end thereof, and contacts on said terminal supports engageable by said movable contact, said movable contact moving between and engaging said insulating members to limit the movement thereof.

15. In a device of the character described, a bracket member, a switch frame mounted thereon, a movable contact element on said switch frame insulated therefrom, a member for actuating the same insulated therefrom extending through said bracket, a lever fulcrumed on said bracket and engaging said actuating member, and means on said lever engaging said bracket to limit the movement thereof.

16. In a device of the character described, switch mechanism, a metallic frame therefor, an insulating housing therefor, a switch actuating member projecting from said housing, a lever for moving said actuating member in one direction, and resilient means for moving said actuating member in the opposite direction, said housing having an opening therein through which said lever is adapted to pass into engagement with said frame when actuated by said resilient means.

17. In a device of the character described, switch mechanism, a metallic frame therefor, an insulating housing therefor, a switch actuating member projecting from said housing, a lever for moving said actuating member in one direction, and resilient means for moving said actuating member in the opposite direction, said frame serving as a

stop for said lever in one direction of its movement.

18. In a device of the character described, switch mechanism, a metallic frame therefor, a bracket depending from said frame having a transversely extending portion having a guide opening and a depending portion, a reciprocable actuating member extending through said opening, a lever pivoted on said depending portion and engaging said actuating member to move the same in one direction, resilient means for moving the same in the opposite direction, and insulating means housing said switch mechanism, said frame acting as a stop to limit the movement of said lever due to said resilient means.

19. In a device of the character described, a bracket member, switch mechanism, a switch actuating member extending through said bracket member, a lever having a bifurcated end, said bracket having a pair of

openings separated by a web, said bifurcations extending through said openings and embracing said web to fulcrum said lever on 25 said frame, said lever engaging said actuating member and means on the free end of said lever for actuating the same.

20. In a device of the character described, a bracket member, switch mechanism, a 30 switch actuating member extending through said bracket member, a lever having a bifurcated end, said bracket having a pair of openings separated by a web, said bifurcations extending through said openings and 35 embracing said web to fulcrum said lever on said frame, said lever passing through an opening in said actuating member and means on the free end of said lever for actuating the same.

In witness whereof, I hereunto subscribe my name this 21st day of October A. D., 1925.

VICTOR R. DESPARD.
